DISPLAY BIN SUPPORTING SHELF

George I. Welter, Chicago, Ill., assignor to Tote-Cart Company, a partnership

Application May 23, 1957, Serial No. 661,230

2 Claims. (Cl. 211—153)

This invention relates to an improved means for supporting merchandise displays and in particular to a support for a display bin comprising wire containers of the type shown in the copending application of Harold I. Sides, Serial No. 636,667, filed January 28, 1957, now Patent No. 2,868,391, wherein the merchandise is dumped into the containers in helter-skelter or jumbled fashion rather than stacked.

In large retail stores commonly in use today, it is necessary to display the merchandise to the purchasing public. Normally, in retail stores such as food stores, which are often referred to as supermarkets, these displays take the form of extensive solid, and hence heavy, shelves on which the merchandise for sale is displayed. Naturally, extensive shelves of this nature are expensive and furthermore tend to be dirt and dust collectors. Moreover, solid shelving presents a visibility problem to the customer in that it tends to hide from view the merchandise on adjacent lower shelves.

The display bin support of this invention overcomes these problems in that it is much less expensive to produce and is light in weight. Moreover, a better visibility of merchandise is afforded while the support will easily hold as much weight as any shelf commonly in use and does not collect dust.

It is therefore, an object of this invention to provide a display bin support adapted to be positioned between a pair of outwardly extending shelf supports which comprises an elongated wire or rod spanner member, means on the spanner member for mounting it on a shelf support, and steady means on the spanner member cooperating with the mounting means to prevent the spanner from rolling on the shelf supports when a display bin is placed thereon.

Other objects of the invention will become apparent from the following description of one embodiment of the invention as disclosed in the accompanying drawings.

Of the drawings:

Fig. 1 is a partial perspective view of shelf supports with display bin supports of this invention positioned thereon and showing in dotted lines a complete and a partially broken away display bin of a common type.

Fig. 2 is an enlarged top plan view, partially broken, of the display bin support of this invention.

Fig. 3 is a side view of the support shown in Fig. 2.

Fig. 4 is an end view of the support.

The display bin supports generally indicated at 10 are designed to be used with shelf supports 11 which are commonly in use today. Normally, these shelf supports 11 are positioned in strengthened members 12 of partitions 13 which are either arranged against the walls (not shown) of the store or on "islands" used to divide the store into aisles. The shelf supports 11 as shown in Fig. 1 are normally arranged so that solid wooden or metal shelves 19 may be positioned thereon to provide a merchandise display or to provide a support for merchandise containers such as baskets.

The display bin supports 10 of this invention which are designed to be positioned on the shelf supports 11

2

comprise an extensive metal spanner wire or rod 14 which is designed to be slightly longer than the distance between the two adjacent shelf supports 11. The ends 14a of the metal rod 14 are bent to form hooks or mounting supports. The hooks 14a are arranged to fit over the shelf supports 11 and prevent the spanner from moving longitudinally. A second metal rod 15 of substantially similar length to the metal rod 14 is provided as a strengthening member. The metal rod 15 has its ends 15a bent at substantially right angles so that the rod 15 may be welded to the rod 14 at 15b. Further strengthening throughout the entire length of the spanner is provided by means of a plurality of short metal rods 16 which are welded to the rods 14 and 15. Thus the display bin support of this invention provides sufficient strength to uphold equally as much display weight as was customarily available with solid shelving.

In using supports such as the one described in this invention, a problem arose, however, since rounded metal rods have a tendency to roll when used between supports such as the shelf supports 11. Because the upper rod 14 is such a rounded metal rod, the flat metal pieces 17 are welded to the rod 14 at substantially right angles to the hooks 14a. Thus the flat metal pieces 17 are substantially parallel to the base of a display bin 18 and are in contact therewith. The flat metal pieces 17 distribute the portion of the weight concentrated on each display bin support equally on each side of the support and prevent it from rolling on the shelf supports 11.

The display bin supports 10 may also be used with solid shelves 19 by simply drilling holes 19a near the ends of the shelves 19 and dropping the hooked ends 14a into the holes as shown in Fig. 1.

Having described my invention as relating to the embodiment shown in the accompanying drawings, it is my intention that the invention be not limited by any of the details of description unless otherwise specified but rather be construed broadly within its spirit and scope as set out in the accompanying claims.

40 I claim:

1. A display bin support adapted to be positioned between a pair of outwardly extending shelf supports, comprising an elongated spanner member having a round cross section with its central portion adapted to extend between said supports in a single plane, said member having down-turned ends forming hooks beyond said supports and relatively thin flat pieces of material attached to the top portion of said spanner member adjacent said end portions.

2. The display bin support of claim 1 wherein a lower rod is attached to said spanner member, the major portion of said lower rod being in a plane parallel to but spaced from said upper rod and with the ends of the lower rod being up-turned and secured to the upper rod wherein there is a plurality of short rods connecting said two rods.
